UNITED STATES PATENT OFFICE.

OLIVER W. JOHNSON, OF CLEVELAND, OHIO.

STACKER FOR FOLDING-MACHINES.

932,283.

Specification of Letters Patent. Patented Aug. 24, 1909.

Application filed September 5, 1907, Serial No. 391,507. Renewed January 11, 1909. Serial No. 471,754.

To all whom it may concern:

Be it known that I, OLIVER W. JOHNSON, citizen of the United States, residing at Cleveland, in the county of Cuyahoga and State of Ohio, have invented certain new and useful Improvements in Stackers for Folding-Machines, of which the following is a specification.

This invention contemplates certain new and useful improvements in stacking devices and relates particularly to a stacking mechanism for folded sheets as they are delivered from a paper folding machine such as that disclosed in my application for Letters Patent of the United States, Serial Number 356,278, filed February 7th, 1907.

For a full understanding of the invention, reference is to be had to the following description and accompanying drawing, in

20 which:

Figure 1 is a side elevation of a portion of the paper folding machine, with my improved stacker incorporated therewith; Fig. 2 is a side elevation thereof, some of the rolls 25 being shown in section; Fig. 3 is a detail view of one of the delivery rolls which form part of the stacking mechanism; Fig. 4 is a detail top plan view illustrating diagrammatically the bottom board or base of the stacking 30 box; and, Fig. 5 is a detail view of one of the curved guide fingers employed.

Corresponding and like parts are referred to in the following description and indicated in all the views of the drawings by the same 35 reference characters.

The paper folding machine with which my improved stacking mechanism is incorporated embodies a series of rolls A³, B³ and C³ extending in horizontal planes in a triangular 40 arrangement, as shown, the paper being pressed downwardly between the rolls A³ and C³ into a folder 96 which is provided with a bed plate 97^a for the sheet, said bed plate being detachably held by means of a set 45 screw 97.

As the sheet passes downwardly between the rolls A³, and C³ into the folder, it is arrested by a stop device 96^a and thus caused to buckle. As the sheet continues to be fed 50 downwardly between the rolls A³ and C³, it will buckle in an evident manner and be caused to pass downwardly in folded condition between the rolls C³ and B³ which thus constitute the crimping rolls of the series. 55 These rolls are driven in any suitable manner

and for a description of the specific means employed, reference is to be had to the application above named.

A folded sheet is delivered from the rolls B³ and C³ and is engaged by means of a series 60 of curved guide fingers 94 that are all supported by means of a transverse bar 95 secured to a portion of the folding machine framework. These curved guide fingers 94 are spaced from each other and direct the 65 folded sheet down into and between the delivery rollers 92 and 93 of the stacking mechanism. The roller 92 is fluted, as clearly illustrated in the drawings and receives its motion from any shaft of the folding machine, by means of a sprocket connection 91.

The paper finally passes down into and between upright stacking arms 98 and 99, the arms 98 being stationary and extending up past the two rollers 92 and 93 by means of 75 grooves in the roller 93, while the stacking arms 99 are relatively movable. The lower ends of the stationary stacking arms are held within brackets 101 which are formed with upper and lower series of wheels 103 upon 80 which the base 102 of the stacking box is mounted to travel in a horizontal plane. This base 102 supports the vertically adjustable platform 104, which is held by means of set collars 104^a upon fingers 99 and 85 coacting uprights 105 that are secured to the ends of the base 102. The base 102 and platform 104 are each composed of a plurality of longitudinally extending boards spaced from each other, as best seen in Fig. 1, 90 or are otherwise formed with channels or slots to accommodate the arms 98, so that the said base and platform together with the relatively movable stacking arms 99 may be moved outwardly to effect the extension of 95 the stacker as the sheets accumulate. The upper ends 100 of the stacking arms 99 are curved outwardly as shown.

In the practical operation, as the folded sheet engages the guides 94, it is thereby deflected downwardly and received in the fluted roller 92 which moves at the same surface speed as the delivery rolls C³ and B³ of the delivery device. At this point, the sheet is fed into the two rollers 92 and 93 on down 100 until the advance edge engages the stacking arms 99 and 98, and on down until the said edge reaches the platform 104 of the stacker. This platform is so set previous to the arrival 105 of the sheet that it will be far enough from 110

the junction of the rolls 92 and 93 to permit the loose or top edge of the sheet to just clear the said rolls, the bend in the guide having caused a strain to be exerted upon the sheet at the top end. The edge of the sheet is thereby caused to bend toward the first flute in the roll 92 that comes around to it after the edge has been released from the engagement of the two rolls. The flutes are of such a nature that they will hook over the edge of the sheet and as the roll continues to turn around, it will force the sheet to bend downwardly until the lower edge engages the platform 104. This should leave the top edge of the sheet still too high to escape the bottom periphery of the roll 92, so that the flute will continue to exert the same influence over the edge and cause it to be shoved to or delivered on the rear side of it. When it finally becomes clear of the said flute, then it has been bent backwardly against the curved upper ends 100 of the rods 99 with the roll 92 between it and the place it formerly occupied. It, therefore, follows that it can never return to its former position and thus room is left for the next sheet to enter. If it is desired that the sheet be fed directly to the stacker from a folding mechanism above the rolls A³, B³ and C³, this result may be accomplished by merely removing the set screw 97 and detaching the plate 97^a which it normally holds. It is then obvious that the sheet will be fed downwardly through the rolls A³ and C³ and be delivered directly to the stacking arms.

As best illustrated in Fig. 1, it will be seen that the fluted roll 92 is grooved like the complementary roll 93, and that the guide fingers 94 extend downwardly and rest with their lower ends in the grooves 92^a of the roll 92. The lower ends of the guide fingers 94 are recessed as indicated at 94^a so as to partially encircle the shaft of the fluted roll 92 and the lower end of the respective guide fingers are formed with convex heel portions 94^b as best seen in Fig. 5. Without the provision of these parts described, the paper when stacked would, when the stacker was partly full, press so hard against the fluted roll 92 after the upper edge of the sheet had been thrown back that the said roll would pull the sheet upwardly and thus disarrange it. By the provision of the heel portion 94^b of each guide finger 94, the sheet is held away from the roll when delivered from the latter and cannot come in contact with the roll 92 after it has once been released therefrom.

By reference to Fig. 4, it will be seen that the bottom board or base 102 of the stacking box tapers toward its rear end. Small rollers 103^a are provided to bear against the side edges of the said base 102, (Figs. 2 and 4) the said rollers being arranged to rotate about vertical axes and mounted in pairs, front and back. When the stacker fills up and moves

away from the complementary rolls 92 and 93, the wedge or tapering shape of the base 102 will manifestly permit the removal of all friction during the operation and when it is shoved back again, it will realine itself and start true at every operation.

Having thus described the invention, what is claimed as new is:

1. In a paper folding machine, the combination with a folding mechanism, of a stacking box adapted to receive the folded paper and embodying a base, roller supports upon which said base is horizontally movable, a vertically adjustable platform supported by the base, relatively movable stacking arms 75 extending above the platform, and relatively stationary stacking arms, the platform being slotted and the stationary stacking arms extending through said slots, whereby to permit the extension movement of the base and 80 platform.

2. The combination with the delivery rolls of a folding machine, of a fluted roll mounted below the delivery rolls, a companion roll for the fluted roll also mounted 90 underneath the delivery rolls, said fluted roll being provided with annular grooves, a stacking box underneath the fluted roll and adapted to receive the product therefrom, and guide fingers extending from the delivery 95 rolls down to the fluted roll and formed at their lower ends with recessed portions partially encircling the shaft of said fluted roll, and a shaft for said roll.

3. The combination with the delivery rolls 100 of a folding machine, of a fluted roll mounted below said delivery rolls, a companion roll for the fluted roll also mounted below the delivery rolls, a stacking box underneath the fluted roll and arranged to receive the product 105 therefrom, a shaft on which the fluted roll is mounted and guide fingers extending downwardly from the delivery rolls to the rear side of the fluted roll, said fluted roll being provided with annular grooves, and the 110 lower ends of the guide fingers fitting in said grooves, said guide fingers being provided at their lower ends with convex heel portions, as and for the purpose set forth.

4. The combination with the delivery rolls 115 of a paper folding machine, of a stacking box adapted to receive the folded paper and embodying a base, vertically and horizontally disposed roller supports upon which said base is horizontally movable, relatively stationary 120 stacking arms extending upwardly from the roller support, uprights secured to one end of said base, relatively movable stacking arms secured to the other end of said base, and a platform adjustably mounted on said uprights and said relatively movable stacking arms, above the base, the base and platform being formed with longitudinally extending slots accommodating the relatively stationary 125 stacking arms.

5. In a stacker, the combination of a transversely grooved and longitudinally fluted roll, a companion roll, guides designed to deliver the sheets or the like to the fluted roll and provided with yoked or recessed ends to receive and hold the sheet from contact with the fluted roll.

6. In a stacking machine, the combination of a longitudinally fluted and transversely grooved roll, a companion roll therefor, guide fingers adapted to direct the product to the fluted roll, a stacking box arranged underneath the fluted roll and adapted to hold articles fed thereto by said roll on edge, the roll being designed to tip the upper edge of

said articles backwardly and the guide fingers being provided with heel portions in the rear of said roll, as and for the purpose set forth.

7. In a stacking box, roller supports, a base mounted to roll on said supports, guide rollers for the side edges of said base, said base being tapered, as and for the purpose set forth.

In testimony whereof I affix my signature 25
in presence of two witnesses.
